UNITED STATES PATENT OFFICE

ALLEN F. FLETCHER, OF ATHOL, MASSACHUSETTS.

PUMP AND VALVE.

SPECIFICATION forming part of Letters Patent No. 367,139, dated July 26, 1887.

Application filed January 8, 1887. Serial No. 223,752. (No model.)

To all whom it may concern:

Be it known that I, ALLEN F. FLETCHER, a citizen of the United States, residing at Athol, in the county of Worcester and State of Massachusetts, have invented certain new and useful Improvements in Pumps and Valves for same; and I do hereby declare the following to be a full, clear, and exact description of the invention, such as will enable others skilled in the art to which it appertains to make and use the same.

My invention is an improvement in pumps, and relates more particularly to an improvement in the valves and boxes which inclose and operate with them. The bodies of the valves for the upper and lower boxes are nearly similar in general form, varying only as to exterior size necessary to render each applicable to its proper place. The valves proper are cast of solid metal of disk form, with annular rabbets between the upper and lower portions, the latter being slightly conical, thus rendering the said bodies thicker at the centers, transversely measured, and thin at the upper or largest diameters. The cones of said valves serve to insure to the valves proper seating after being lifted from their places. In preparing one of these valves for use, I form an annular groove at the junction of the horizontal and vertical portions of the said annular rabbet for the reception of a packing-ring, which latter when in place rests against the under side of the horizontal portion of said rabbet and within the said annular groove. The packing, which is preferably of leather, is cut in the form of a flat ring, the opening of which is of a diameter less than the diameter of the valve-body at the bottom of the said annular groove. Before placing the packing upon the valve it is made thoroughly wet, and then forced over into the annular groove and up against the under side of the flat portion of the disk, where it binds and fits snugly when dry. There is a lower and upper box provided to receive each one of these valves, the lower of which is arranged to be fixed firmly in the well-tube, and the upper is in the form of a piston, adapted to play up and down during the movement of the piston or pump rod. Both of said boxes are cup-shaped and somewhat conical in exterior form, each being provided with a bottom portion with an opening provided for the

passage of the fluid. The depth of the cone of the lower box is preferably somewhat deeper than that of the upper box. The exterior surfaces of the cones in both boxes are horizontally grooved, so that annular recesses may be formed to receive packing-rings. The packing for these boxes is cut of proper size from a sheet of packing material, and before being fitted to place, like the rings for the valves, are made thoroughly wet, so that they may be expanded and made pliable before being pressed to place over the cones. When they shrink they conform exactly to their respective grooves, and are held from slipping off between the flanges formed by the cutting of said grooves. The lower of the said boxes is provided with a bridge formed across its top, which arches upward and forms a rest for the upper box when the latter is down and at rest. At the base of this bridge a lever of peculiar form is pivoted or hinged, one arm of which is hooked to a loop in the top of the lower valve. The other arm of said lever, extending upward, is finished with a knob which receives the weight of the upper box and yields, thus opening the lower valve to allow the fluid to pass downward through said box. The upper box has cast within its cup, and extending upward, several lugs which serve as guides to the valve in its vertical movement. This upper box is also provided with a bridge, and in the center of said bridge is formed a screw-threaded socket, provided to receive the pump or piston rod.

In the drawings illustrating my invention, Figure 1 is a sectional view of a well-tube, with the boxes and valves within the same. Fig. 2 is a plan or top view showing the lower box. Fig. 3 is a similar view showing the upper box, &c. Figs. 4 and 4^a show samples of the packing-rings as cut from the sheet of packing material.

Similar reference-letters indicate like parts in all of the figures.

Referring to the drawings, A is the box, located at a proper point in the well-tube X, having a horizontal bottom provided with a circular opening, f, and side wall, g, of conical form. From the upper edge of this conical wall springs the bridge F, and at the base of this bridge, beneath its center, is hinged the lever E.

D is a valve, of disk form, provided with an annular groove, *a*, which receives and holds the packing-ring *a'*, which latter bears against the under side of the cut away portion of said valve. The valve D, when in place, rests with its packing-ring bearing upon the bottom of the box A, its conical portion extending partly through the opening *f*. When said valve falls, should the conical surface of its bottom strike 5 upon the diaphragm of the box, it would be immediately shunted, so as to bring the packing upon the valve-seat. Upon the top of the valve D is a loop, *b*, which receives the hook-shaped end of the lever E, by which the said 10 valve is raised to allow the fluid above the box A to pass through the opening *f*.

The box A is provided with packing *i*, snugly fitted about its conical exterior to form a tight joint between the tube X and the said 15 box.

The upper box, B, has a form similar to that of box A, but preferably more shallow. On the upper edge of the circular wall of this box is a bridge, G, provided with a screw-threaded 20 socket, *J*, which receives the screw-threaded end of the pump rod *d*. From the upper surface of the bottom of the box B rise several studs, *e*, which serve as guides to the valve D' during its movement. The valve D', as 25 previously stated, is formed like that of D, and it bears when in place over the opening of the box B, its packing-ring, like that of the valve below, resting upon the upper surface of the bottom of said box. The exterior conical portions of the boxes A and B are grooved, as 30 shown, so as to form convex surfaces for the packing-rings which envelope them to bind and hold upon. A pin, *e'*, is provided to run through the socket *j* and project on either side 35 of same horizontally to prevent the valve below from jumping out of place when lifted.

In operating the pump the box B is lifted

and lowered by its rod *d*, in the usual manner of pump-pistons. The partial vacuum formed by the lifting movement of said box gives 45 place to the fluid, which lifts the valve and rushes through the opening in the box A, filling the space between the two boxes. When a downward movement is made to the box B, the fluid below closes the valve D and lifts the 50 one D', and finds its way through the opening in box B. When said box B is again lifted, the fluid is discharged from the well-tube in the usual manner. When it is desirable to empty the box A entirely, the upper box is 55 moved downward until the lower surface of its bottom comes in contact with the upwardly-extending arm of the lever E. Said lever now yields and lifts the valve D from its seat, and immediately thereafter the valve D' comes 60 in contact with the bridge F, by which latter said valve is also lifted to empty the upper box.

It may be observed that no hinges are employed to form the axes of motion of the 65 valves, and consequently their construction is simplified and they are rendered easy of application and removal.

Having thus described my invention, what I claim as new, and desire to secure by Letters Patent, is—

The combination, with a pump-box provided with a bridge and a lever hinged at the base of the same, of the tilting valve provided with a loop to engage a hook of said lever, and 75 a back bearing to rest against the interior of the box-wall while the said valve is being tilted, as and for the purpose set forth.

In testimony whereof I affix my signature in presence of two witnesses.

ALLEN F. FLETCHER.
